(57) CLAIM

The ornamental design for a food roasting stick, as shown and described.

DESCRIPTION

FIG. 1 is a top plan view of the stick;
FIG. 2 is a right side elevational view;
FIG. 3 is a front elevational view;
FIG. 4 is a rear elevational view;
FIG. 5 is a bottom plan view; and,
FIG. 6 is a perspective view.

The broken line drawings of the foods mounted in the roasting stick are for illustrative purposes only and form no part of the claimed design.
